UNITED STATES PATENT OFFICE.

JAMES B. LEE, OF SAVANNAH, GEORGIA.

DESIGN FOR A SET OF LETTERS AND OTHER CHARACTERS.

42,766.

Specification for Design.

Patented July 9, 1912.

Application filed May 13, 1912. Serial No. 697,039. Term of patent 14 years.

To all whom it may concern:

Be it known that I, JAMES B. LEE, a citizen of the United States, residing at Savannah, in the county of Chatham and State of Georgia, have invented a new, original, and ornamental Design for a Set of Letters and other Characters, of which the following is a specification, reference being had to the accompanying drawing, forming a part thereof.

The figure, extended over two sheets, gives a front view of the series of letters and other characters (Arabic numerals and the interrogation mark and the dollar mark), showing my new design.

I claim:

The ornamental design for a set of letters and other characters, as shown.

In testimony whereof I have signed my name, in presence of two witnesses, this 10th day of May, in the year one thousand nine hundred and twelve.

JAMES B. LEE.

Witnesses:

CYRUS KEHR,
W. W. LEE.
